DESIGN FOR A HAT

Kenneth W. Johnson, New Haven, Conn.

Application March 25, 1941, Serial No. 99,871

Term of patent 7 years

To all whom it may concern:

Be it known that I, Kenneth W. Johnson, a citizen of the United States, residing in New Haven, in the county of New Haven and State of Connecticut, have invented a new, original, and ornamental Design for a Hat, of which the following is a specification, reference being had to the accompanying drawing forming a part thereof, and in which—

Fig. 1 is a side elevational view of a hat showing my design as it appears when worn;

Fig. 2 is a front elevational view of the hat shown in Fig. 1; and

Fig. 3 is a side view thereof on a slightly reduced scale as it appears when lying flat.

I claim:

The ornamental design for a hat, substantially as shown and described.

KENNETH W. JOHNSON.
